UNITED STATES PATENT OFFICE.

WILHELM BERTIL BRONANDER, OF MONTCLAIR, NEW JERSEY.

TWO-STROKE-CYCLE OPPOSED-PISTON INTERNAL-COMBUSTION ENGINE.

Application filed September 26, 1919. Serial No. 326,590.

To all whom it may concern:

Be it known that I, WILHELM BERTIL BRONANDER, a citizen of the United States, residing at Montclair, in the county of Essex, 5 State of New Jersey, have invented certain new and useful Improvements in Two-Stroke-Cycle Opposed-Piston Internal-Combustion Engines; and I do hereby declare the following to be a full, clear, and exact description of the invention, such as will enable others skilled in the art to which it appertains, to make and use the same.

This invention relates to improvements in two-stroke-cycle opposed-piston internal 15 combustion engines in which the pistons are utilized for controlling the cylinder ports and the charge of fuel is given a preliminary compression before being introduced into the cylinders between the pistons.

20 In my copending application, Serial No. 312,688, filed July 23, 1919, there is disclosed an engine which overcomes the disadvantages of the usual types of two-stroke-cycle engines in which the pistons are utilized for controlling ports in the walls of the cylinders. These prior engines, as usually constructed, comprise a number of separate cylinders each provided with inlet ports which are uncovered by the piston as it approaches the 25 bottom of the cylinder to allow a charge of gas, which has been given an initial compression to enter the cylinder. Each cylinder is also provided with exhaust ports which must be so arranged with respect to

30 the inlet ports that they are uncovered before the inlet ports, as the piston approaches the bottom of the cylinder to permit the greater portion of the waste gases to escape before the inlet ports are uncovered. When the inlet ports are uncovered, a charge of gas under 35 pressure will enter the cylinder and aid in sweeping out the waste products, but on account of the arrangement of the inlet and exhaust ports the latter will not be covered

40 until an appreciable time after the inlet ports have been closed by the piston as it moves upward on the next stroke, so that some of the charge may escape from the exhaust ports, the amount depending upon the interval 45 between the closing of the two sets of ports as determined by the speed of the engine. Due to the escape of more or less of the charge, the advantages of its initial compression are, in a measure, lost and the efficiency of the engine is correspondingly reduced.

The invention covered by my copending application referred to above comprises a two-stroke-cycle internal combustion engine in which each power unit comprises a pair 60 of communicating cylinders each provided with a piston. The piston of one of the cylinders controls exhaust ports in the wall of of the cylinder and also carburetor or supply ports through which the gas is supplied 65 to the crank case of the engine. The other piston controls inlet ports in the wall of the other cylinder through which a charge is supplied to the cylinders after being given an initial compression in the crank case of 70 the engine. The two pistons of each unit are connected to the crank shaft of the engine in such a manner as to cause the piston controlling the exhaust ports to uncover these ports before the piston in the other cylinder 75 has uncovered the inlet ports on the working strokes of the pistons, and on the reverse or compression strokes the piston controlling the exhaust ports will again travel in advance of the other piston so as to cover the 80 exhaust ports before the other piston has covered the inlet ports. There is thus an interval during which both the exhaust and inlet ports will be open so that the incoming 85 charge of compressed gas will sweep out of the cylinders such waste gases as did not escape when the exhaust ports were first uncovered.

Various types of internal combustion engines in which two pistons are arranged 90 in a common cylinder so as to work in opposite directions, have been constructed, the general object of these arrangements being to obtain double the power of a gas engine of the same kind without increasing the 95 diameters of the cylinders and with a lesser number of working parts than would be required were the same increase in power obtained by providing additional separate cylinders with their necessary adjuncts. As 100 these engines have usually been constructed, each power unit comprises a single elongated cylinder having near one end a series of exhaust ports which are controlled by one of the pistons, and near the other end a 105 series of ports through which scavenging air is introduced and beyond these ports a series of inlet ports through which the fuel charge is supplied, both of these series of ports being controlled by the other piston. 110 Two-stroke-cycle engines of this general construction are open to the same objections as

are the types of two-stroke-cycle engines described above in which a single piston controls both the exhaust and inlet ports in the same cylinder, namely, that the exhaust ports 5 must be arranged to be uncovered by one of the pistons before the inlet ports are uncovered by the other piston to permit the waste gases to escape as the pistons move apart during their working stroke, and 10 since the exhaust ports are uncovered before the inlet ports, they will remain open after the inlet ports have been closed during the opposite or compression stroke of the pistons. There is, accordingly, a possibility that some 15 of the charge supplied to the cylinder will escape through the exhaust ports, and the slower the speed of the engine the greater will be the amount of charge that may escape. As in the case of single piston engines, 20 the advantage of the initial compression of the fuel is thus in a measure lost, and the efficiency of the engine is correspondingly reduced.

Various attempts have been made to overcome this defect in engines of this type, such 25 as throttling devices or valves adapted to be operated in such a manner as to permit a free discharge of the products of combustion during the earlier part of the exhaust period and to check the exhaust outlet to allow the building up of pressure of the incoming charge so that the advantages of the initial compression of the charge are retained. Such arrangements, however, require 30 the provision of relatively complicated valves which must be operated in timed relation to the other parts of the engine and are in addition usually made responsive to the load on the engine, as by being controlled 35 by a governor so as to vary the throttling effect in accordance with the demands upon the engine.

In a companion application, Serial No. 326,589, filed of even date herewith, there 40 is shown, described and claimed a two-stroke-cycle, opposed-piston internal combustion engine in which the disadvantages of engines of this type as usually constructed are overcome by an application of the principles 45 of the invention of my copending application, Serial No. 312,688. In accordance with the invention of the companion application each power unit of the engine comprises a pair of elongated, parallel cylinders which 50 are in communication with each other at a point midway between their ends and in each of which is a pair of pistons adapted to move in opposite directions. The ends of these cylinders are in communication 55 with gas-tight crank cases in which the preliminary compression of the fuel charge takes place and which are adapted to be placed in communication with the cylinders through two series of inlet ports in the walls 60 of the cylinders, which are controlled by

two of the four pistons of the unit. The charges of fuel are admitted to the crank cases through supply ports in the walls of the cylinders, which are uncovered by the other two pistons when they are at the inner 70 ends of their strokes. Adjacent the supply ports, but nearer the center of the cylinders are exhaust ports which are uncovered by the same pistons that control the supply ports, when these pistons are at the outer 75 ends of their strokes.

The pistons are connected in pairs to two crank shafts of the engine in such a manner that as they move outwardly on the working stroke the two pistons that control the 80 exhaust ports will uncover these ports before the two pistons that control the inlet ports have uncovered the latter ports, and on the reverse or compression stroke the piston controlling the exhaust ports will again travel 85 in advance of the other piston so as to cover the exhaust ports before the latter pistons have covered the inlet ports. There is, accordingly, an interval during which all of the 90 exhaust and inlet ports are simultaneously opened so that the charges of compressed gas which are permitted to enter the cylinders will sweep out such waste gases as did not escape when the exhaust ports were first uncovered. The gases will rush through the 95 cylinders and through the opening between them and effectively scavenge all parts of the same. Since the exhaust ports are always closed before the inlet ports there is no diminution of pressure, and the compression under which the gas is supplied to the 100 spaces between the pistons is maintained. The arrangement possesses the further advantage that it avoids the use of all projections or baffles such as are frequently provided at the tops of pistons in engines of the two-stroke-cycle type in which each piston controls inlet and exhaust ports in the walls of the same cylinder, and which tend to cause the formation of pockets of gas. Furthermore, the manner in which the pistons are connected to the crank shafts permits a longer stroke with the same throw of the cranks than could be obtained by a single 105 piston connected to a crank shaft in the usual manner.

As disclosed in my companion application Serial No. 326,589, the preferred embodiment of the invention comprises an engine in which one series of inlet ports is arranged in the wall of one of the cylinders toward the end of the cylinder that communicates with one of the crank cases while the other series of inlet ports is correspondingly arranged in the wall of the other cylinder toward the end that communicates with the other crank case, adjacent carburetor and exhaust ports being placed at the end of each cylinder opposite to the end at which the inlet ports are placed.

With this arrangement of the ports, it is necessary that the two shafts rotate in the same direction in order that the mechanism by which they are connected to the pistons shall cause the pistons to control the ports in the desired manner. In many cases it may be required that the shafts be driven in opposite directions, and the present application is directed particularly to an embodiment of the invention of my companion application which meets this requirement and also provides for other modifications in the arrangements of the ports, which may be desirable in practice.

In accordance with the present invention both series of inlet ports are arranged toward opposite ends of one cylinder and are controlled by the two pistons therein, while, the two sets of adjacent exhaust and supply ports are arranged toward opposite ends of the other cylinder and are controlled by the two pistons therein. The two cylinders are in communication so that incoming fuel charge may pass from the first named cylinder into the other, while the waste gases also follow the same course to reach the exhaust ports. With this arrangement of the ports the shafts must rotate in opposite directions in order that the pistons may function in accordance with the invention.

The particular nature of the invention, as well as other objects and advantages thereof, will appear more clearly from a description of a preferred embodiment as shown in the accompanying drawings in which:—

Fig. 1 is a longitudinal section through one of the power units of the engine at right angles to the crank shafts;

Fig. 2 is a transverse section of the unit along the line 2—2 of Fig. 1;

Fig. 3 is a similar section along the line 3—3 of Fig. 1; and

Figs. 4 to 7 inclusive are diagrams showing successive positions of the moving parts of the engine.

It will be understood that the engine may be composed of as many units as desired, but since these units are all of the same construction only one of them has been shown in the drawings and will be described in the following specification. In the drawings, in which similar reference characters denote similar parts throughout the several views, 20 is a casing provided with a pair of circular inner walls 21 which merge together as at 22, thus forming a pair of elongated, adjacent, parallel cylinders A and B separated by a center wall, which at a point midway between the ends of the cylinders, is provided with an aperture 23 to permit communication between the cylinders. The casing 20 is provided with an outer wall 24 which forms in connection with the cylinder walls a chamber through which a cool-

ing liquid may be circulated by means of suitable pipe connections. At each end of the casing, the wall 24 is carried outwardly as at 25, and the ends of the chamber are formed by partitions 26, so that there is thus formed in each end of the casing a space which is divided into two chambers 27 and 28 by a partition 29 extending from the wall 22 between the cylinders to the outer wall 24 and the corresponding partitions 26 as shown most clearly in Figs. 2 and 3. The outer ends of the chambers 27 are in communication with the interiors of gas-tight crank cases 30 attached to the ends of the casing in any suitable manner. The inner ends of both chambers 27 are in communication with cylinder A through a number of inlet ports 31. The two chambers 28 communicate with the other cylinder B through exhaust ports 32, and at the side of the casing the chambers are provided with enlarged ports 33 to which exhaust manifolds may be connected, it being understood that the manifolds of each unit may merge into a common manifold to which the manifolds of the other units of the engine may also be connected. Between the exhaust ports 32, and the ends of cylinder B are supply ports 34 which communicate with chambers 35 formed between the wall of this cylinder and the outer wall of casing 20 and each separated from the adjacent chamber 28 by a partition 36. Each of the chambers 35 is provided with an enlarged port 37 adapted to be connected to a gas-supply manifold, and as in the case of the exhaust manifolds, the supply manifolds of each unit may merge into a common manifold leading to a carburetor. The heat transmitted through the partitions 36 from the exhaust gases discharged through the ports 32 will raise the temperature of the incoming fuel charges. Each of the cylinders is provided at a point midway between its ends with a suitable spark plug 38 for igniting the charge within the cylinder.

Mounted in suitable bearings at opposite ends of the unit are shafts 39, it being understood that these shafts are common to the several units of which the engine is composed and each is provided at the points where it passes through the walls of the crank cases with suitable bushing to prevent escape of gas from the crank cases. Each of the shafts 39 is provided with cranks 40 for each unit of the engine, and each crank has a pin 41 upon which is journaled a member 42 having extended ends to one of which is rigidly attached, as by being formed integrally therewith, a connecting rod 43 which is pivotally attached as at 44 to one of the pistons 45 of one cylinder. Attached to the other extended end of member 42, as by means of a journal 46, is the forked end of a connecting rod 47 which is pivotally 130

attached to the companion piston 48 of the other cylinder. It is necessary to provide a pivotal connection between one of the connecting rods and the member 42 attached to the crank pin to allow for slight variations in the parallelism of the two connecting rods which occur during the movement of the parts.

It is necessary that the two main shafts 10 be connected to each other in order that the correct operative relation between both pairs of pistons shall be maintained. As indicated on the drawings this connection comprises a transverse shaft 49 geared to 15 each of the main shafts 39 by suitable bevel or other gears; but it will be understood that any other suitable arrangement may be employed for connecting the main shafts to each other.

20 It will be seen from the above description of the apparatus that there is provided a twin-cylinder opposed-piston power unit in which the halves of the unit are of similar construction, and the corresponding ports and pistons are so arranged that the pistons 25 of cylinder A control the two sets of inlet ports 31 of the unit, and the pistons of cylinder B control the two sets of exhaust ports 32 and carburetor ports 34 of this 30 cylinder, while both pairs of companion pistons are connected to the crank shafts in a manner similar to that shown in my co-pending application, Serial No. 312,688.

The operation of the engine can be explained most clearly by the aid of the diagrams of Figs. 4 to 7, inclusive. Assuming that both of the crank pins of the unit are at their inner dead centers, each pair of companion pistons will be at the inner limits of 40 their strokes and their faces will be in the same plane. The two crank shafts are assumed to be rotating in the directions indicated by the arrows in Figs. 4 to 7, inclusive. As the crank pins of both pairs of pistons 45 move away from their dead center points, the pistons 45 in cylinder B will move outwardly a slight amount, while the companion pistons 48 in cylinder A will move slightly toward each other, and Fig. 4 shows the positions of the pistons at this stage of operation. In any internal combustion engine the explosion should take place when the case is under greatest compression, as it is when the piston is at the limit of its inward stroke, 55 but at this time the crank to which the piston is connected will be on dead center and some power will be lost when the charge is then fired. It is of advantage to have the explosion occur immediately after the crank has 60 passed over the dead center, but there will then be a loss in the compression of the charge due to the increased space in the cylinder. With the present arrangement ignition may take place after the cranks have 65 passed their dead centers, for the slight outward movement of pistons 45 is compensated by a corresponding inward movement of pistons 48, so that the charge of gas between the opposed pistons is kept under maximum compression at the instant of firing, there being communication between the two cylinders through aperture 23 so the pressure is equalized.

During the working stroke both pistons 45 move outwardly more rapidly than do the 75 pistons 48 so that during this stage of operation each pair of companion pistons has the general relation shown in Fig. 1. When the pistons 45 are at the inner ends of their strokes, both sets of carburetor ports 34 will 80 be uncovered to permit a fuel charge to pass into each crank case. As each piston 45 moves outwardly it covers the corresponding ports 34, and since the corresponding inlet ports 31 are covered by the pistons 48, the 85 charges in the crank cases of the unit will be compressed by the pistons. Each piston 45 will continue to travel in advance of its companion piston 48 and will finally reach the position shown in Fig. 5 where the exhaust ports 32 will be uncovered to permit the waste gases to escape from the cylinders, the gases from cylinder A passing through aperture 23 into cylinder B. Shortly thereafter the pistons 48 will, as shown in Fig. 6, 90 reach a position where the inlet ports 31 will be uncovered, so that the fuel charges which are under compression in the crank cases, may enter cylinder A and pass through aperture 23 into cylinder B. As all of the 95 exhaust ports 32 are also open, the advance of the charges through cylinder A, and into cylinder B will sweep out any waste gases that have not already escaped through the exhaust ports. While this scavenging operation is occurring, the cranks are passing over their lower dead centers and the pistons occupy the positions shown in Fig. 6.

On account of the arrangement by which the pistons are connected to the crank shafts, 110 pistons 45 will then move inwardly ahead of their companion pistons 48 to close the exhaust ports 32 while the inlet ports 31 are still open as indicated in Fig. 7. The moving parts of the unit should be so timed that 115 both sets of exhaust ports 32 will be covered just before the incoming charges reach these ports during their progress through the cylinders. Due to the lag of pistons 48 behind pistons 45 during their inward movement, 120 the inlet ports 31 will remain open a sufficient interval of time after the exhaust ports 32 have been closed to permit a full charge to be supplied to both of the cylinders. The pistons 48 will finally cover the inlet ports 125 31, and thereafter the pistons move inwardly on the compression stroke, pass over their inner dead center points and reach the position indicated in Fig. 4 where the charges in the cylinders will be ignited. The in- 130

ward movement of the pistons will create a vacuum in each of the crank cases so that when pistons 45 have uncovered the carburetor ports 34 a charge of gas will rush into each crank case from the carburetor to be compressed on the next stroke of the pistons.

From the above description it will be seen that the invention provides a two-stroke-cycle, opposed-piston engine in which all of 10 the exhaust ports are opened ahead of the inlet ports on the working stroke and also closed ahead of the inlet ports on the compression stroke so that pressures higher than that of the atmosphere may be obtained in 15 the cylinders before the compression strokes begin, there being no loss of compression as in the case of the usual types of engines in which the exhaust ports cannot be closed until after the inlet ports have been closed 20 on account of the construction of the engines.

The arrangement of the two cylinders in parallel relation with a single wall between them having an aperture therein, provides 25 for the most effective scavenging of the cylinders, for the incoming charges of compressed gas will rush from the ends of one cylinder, through this aperture and into the other cylinder, with the result that all of 30 the residues of combustion that did not escape when the exhaust ports were first uncovered will be swept out of the cylinders. This improved scavenging effect is obtained without the use of baffles or other 35 projecting members upon the pistons, so that there are no pockets in which waste gases may collect, and it is not necessary to provide any superfluous space between the inner ends of the pistons to take care of 40 such projecting members. The arrangement by which the pistons are connected to the cranks of the engine also permits them to have a slightly longer stroke than would be obtained by a single piston connected to 45 a crank of the same radius.

While only one unit has been shown and described above, it will be understood that a complete engine will comprise a number of such units which will be connected to the 50 crank shafts in such angular relations as will produce the most effective operation. In the embodiment of the invention herein shown, the two crank shafts rotate in opposite directions, but by the provision of 55 suitable gearing in connection with one of the shafts, the members driven by the shafts may be rotated in the same direction. By employing the arrangement shown in my companion application, Serial No. 326,589, 60 filed concurrently herewith, no such gearing is necessary as the two crank shafts rotate in the same direction. While the invention has been illustrated in connection with an engine that is fired from a spark 65 plug, it should also be understood that the

invention is applicable to the Diesel type of engine, in which a heavy oil is injected directly into the combustion chamber. It will also be understood that various other changes in the details of construction of 70 the apparatus may be made without departing from the principle of the invention as defined in the appended claims.

I claim:

1. An internal combustion engine, comprising a pair of communicating cylinders, inlet ports in one cylinder and exhaust ports in the other cylinder, opposed pistons in each cylinder adapted to control the ports therein, a pair of crank shafts associated 75 with the cylinders, and adapted to rotate in opposite directions, and connections between the crank shafts and the pistons arranged to cause the pistons controlling the inlet ports to lag behind the pistons controlling the exhaust ports during each stroke of the pistons.

2. An internal combustion engine, comprising a pair of crank shafts adapted to rotate in opposite directions, a pair of communicating cylinders arranged between the crank shafts, inlet and exhaust ports in the walls of the cylinders, opposed pistons in each cylinder adapted to control the ports therein, and connections between the 90 pistons and the crank shafts arranged to cause the pistons controlling the inlet ports to lag behind the pistons controlling the exhaust ports during each stroke of the pistons so that the exhaust ports are opened 95 ahead of the inlet ports during the working strokes and closed ahead of the inlet ports during the compression strokes.

3. A two-stroke-cycle internal combustion engine, comprising a pair of crank shafts 105 adapted to rotate in opposite directions, a pair of communicating cylinders arranged between the crank shafts, inlet and exhaust ports in the walls of the cylinders, a pair 110 of pistons in each cylinder adapted to control the ports therein, and means operatively connecting the pistons to the crank shafts for causing the pistons controlling the exhaust ports to uncover these ports before the pistons controlling the inlet ports have 115 uncovered their ports during the working strokes and to cover the exhaust ports before the last-named pistons cover the ports during the compression stroke.

4. An internal combustion engine, comprising a pair of parallel cylinders having a common dividing wall provided with an aperture midway between the ends of the cylinders to permit communicating between the cylinders, inlet and exhaust ports in 125 the walls of the cylinders, opposed pistons in each cylinder adapted to control the ports therein, power transmitting means adjacent the ends of the cylinders adapted to rotate 130 in opposite directions, and connections be-

tween the power transmitting means and the pistons arranged to cause the pistons controlling the inlet ports to lag behind the pistons controlling the exhaust ports during each stroke of the pistons.

5. An internal combustion engine, comprising a pair of communicating cylinders, inlet ports in the wall of one cylinder toward the ends thereof, exhaust ports in 10 the wall of the other cylinder toward the ends thereof, pistons in the first-named cylinder for controlling the inlet ports therein, pistons in the second-named cylinder for controlling the exhaust ports therein, a 15 crank shaft adjacent each end of the cylinders, connections between each crank shaft and the adjacent pistons of the two cylinders arranged to cause each inlet port controlling piston to lag behind its companion 20 exhaust port controlling piston during each stroke of the pistons.

6. An internal combustion engine, comprising a pair of communicating cylinders, inlet and exhaust ports in the walls of 25 the cylinders, a pair of pistons in each cylinder adapted to control the ports therein, a pair of shafts adjacent the ends of the cylinders adapted to rotate in opposite directions, a crank connected to each shaft, a 30 member movably mounted on the crank, a rigid connection between one end of the member and one of the pistons of one cylinder, and a movable connection between the other end of the member and the companion 35 piston of the other cylinder, each member

and the connections between it and the corresponding pistons being so constructed as to cause the piston controlling the exhaust port to uncover this port before the piston controlling the inlet port has uncovered its 40 port during the working strokes and to cover the exhaust port before the last-named piston covers the inlet port during the compression strokes of the engine.

7. An internal combustion engine, comprising a pair of communicating cylinders, inlet and exhaust ports in the walls of the cylinders, a pair of pistons in each cylinder adapted to control the ports therein, a pair of shafts adjacent the ends of the 45 cylinders adapted to rotate in opposite directions, a crank connected to each shaft, a member movably mounted on each crank and provided at one end with an integral rod connected to one of the pistons of one 50 cylinder, a rod pivotally connected to the other end of the member and attached to the companion piston of the other cylinder, the members and their connecting rods being so arranged that during rotation of the 55 shafts both of the pistons controlling the inlet ports will lag behind the pistons controlling the exhaust ports during each stroke of the pistons so that the exhaust ports are opened ahead of the inlet ports during 60 the working strokes and closed ahead of the inlet ports during the reverse strokes.

In testimony whereof I affix my signature.

WILHELM BERTIL BRONANDER.
